UNITED STATES PATENT OFFICE.

SYLVESTER MARSH, OF CHICAGO, ILLINOIS.

IMPROVED APPARATUS FOR RENDERING LARD, &c.

Specification forming part of Letters Patent No. 41,781, dated March 1, 1864.

To all whom it may concern:

Be it known that I, SYLVESTER MARSH, of Chicago, in the county of Cook and State of Illinois, have invented a new and useful Apparatus for Rendering Lard, Tallow, or other Fatty Substances; and I do hereby declare that the following is a full, clear, and exact description of the same, reference being had to the accompanying drawings, in which—

Figure 1 is a perspective view, and Fig. 2 a sectional elevation, of my improved apparatus.

The mode of rendering lard or tallow, or other similar fatty substances—*i. e.*, the melting of the raw lard, tallow, &c.—for the purpose of refining the same, so as to free them from the filaments or other foreign matter they may contain, also from the water which is held in intimate mixture combined with them, was heretofore practiced in kettles or caldrons of a semispherical structure established upon a fire-chamber or furnace provided with a short chimney on one side of the said kettle or caldron. There are many objections to this mode of rendering lard, &c., among which I will mention, first, impracticability of using large kettles or caldrons because of the difficulty attending the stirring and emptying of such kettles, or caldrons; secondly, waste of heat—the heat rendered available is that directly thrown out by the radiation from the fuel, while the heat of the flame or other products of combustion is nearly wholly lost; thirdly, liability of the lard or other fatty matter becoming scorched or discolored; fourthly, impossibility of emptying by means other than ladles, &c.

The object of my invention is to remove these and other objections; and it consists, first, in the employment, in the art of rendering lard, tallow, or other fatty matter, of an elongated semi-cylindrical vessel, or vessels of other form substantially the same, so that large quantities of matter may be operated upon with ease, while the heat emitted by the burning of the fuel is more perfectly utilized than heretofore; second, in the employment, in the art of rendering lard, tallow, or other fatty matter of an elongated heating-vessel, having at one end a drain-pipe provided with faucets or cocks to cut off the flow of liquefied mass at pleasure; third, in the employment, in combination with an elongated vessel for rendering lard, tallow, or other fatty matter

provided with a drain-pipe and faucet, of a strainer within the boiler, arranged in any convenient manner.

To enable others to make and use my invention, I shall now proceed to describe a rendering kettle or boiler constructed in accordance with my invention.

In the accompanying drawings is the masonry or brick-work which constitutes the foundation or base to the apparatus subject of this patent. It is composed of a fire-chamber, B, with the usual grate, ash-pit at the one end, and of a chimney, C, for carrying off the smoke and gases at the other end, the intermediate space inclosed by brick walls performing the functions of a heating-flue. The front and rear walls of this base or brick foundation are rounded on the top, and form the supports of the boiler or kettle. The boiler proper, which is or may be made of cast-iron, or of any other metal, is of a semi-cylindrical form, somewhat like a trough, and may be provided with horizontal flanges along the top, whereby it rests upon the brick-work. The ends are closed by vertical plates P, or convex or spherical caps. Near the rear end of the kettle there is a vertical partition, D, composed of a perforated sheet metal, for the purpose of straining the liquefied fat and separating it from the filaments and other foreign matter. In the rear-end plate there is a drain-pipe, E, provided with a faucet to regulate and stop the flow or outlet of the refined fat at pleasure.

To operate this simple yet improved kettle, no special instructions are necessary. The advantages, however, should be known for the more intelligent working of the apparatus.

One man can attend to a kettle of about twenty-five feet in length by two and a half feet (more or less) wide and deep, and operate at one operation on a mass of from three hundred to three hundred and fifty gallons of lard or tallow. He gradually throws the raw material into the kettle at the forward end—*i. e.*, the end over the fire-chamber—and from time to time stirs the mass by means of paddles or spades, following along the sides of the boiler. In this way he can stir the whole mass without inconvenience. The melted mass forms on the bottom and the scraps float on top, which may be taken off by means of perforated ladles. When the mass is sufficiently

liquefied, the attendant opens the faucet and allows the liquid mass to flow out to be collected in suitable vessels or coolers. During the flow the light scraps are retained in the body of the boiler by the straining-plate.

Having thus fully described my said invention, and the manner in which the same is or may be carried into effect, I claim—

1. The employment, in the art of rendering lard, tallow, or other fatty matter, of an elongated semi-cylindrical vessel, or vessels of other form substantially the same, so that large quantities of matter may be operated upon with ease, while the heat emitted by the burning of the fuel is more perfectly utilized than heretofore.

2. The employment, in the art of rendering

lard, tallow, or other fatty matter, of an elongated heating-vessel, having at one end a drain-pipe provided with faucets or cocks to cut off the flow of liquefied mass at pleasure.

3. The employment, in combination with an elongated vessel for rendering lard, tallow, or other fatty matter provided with a drain-pipe and faucet, of a strainer within the boiler, arranged in any convenient manner.

In testimony whereof I have signed my name to this specification before two subscribing witnesses.

SYLVESTER MARSH.
